VULCANIZING EQUIPMENT

Mathias J. Daheim and Frank L. Finn,
Minneapolis, Minn.

Application April 16, 1947, Serial No. 741,792

2 Claims. (Cl. 18—18)

1

Our invention relates to vulcanizing equipment and is designed primarily for applying patches to inner tubes of pneumatic tires.

The primary object of our invention is the provision of vulcanizing equipment, incorporating a bed plate, a bridge beam, a pressure shoe interposed between the bed plate and the bridge beam and carried by the latter, and means for clamping said bridge beam to said bed plate, in which the pressure shoe is permitted to rock in but one plane.

Another important object of our invention is the provision of such a structure having an elongated pressure shoe, which is mounted on said bridge beam by a head and socket connection which permits rocking movements thereof, under set conditions, only in a vertical plane longitudinally of the bridge beam. Under the above novel arrangement, the pressure shoe is maintained at all times in parallel relationship to the bed plate, irrespective of the thickness of the material placed therebetween.

It is a further object of our invention to provide a pressure pad intermediate the bed plate and the pressure shoe, which is made from rubber-like resilient material capable of being displaced sufficiently to compensate for the differences in thickness in the material being vulcanized, with the result that a uniform degree of heat is brought to bear upon all of the tube underlying the pressure shoe.

Another object of our invention is the provision of a novel combination of elements including a pressure shoe having a soleplate with a central recess therein adapted to receive a plurality of different shaped inserts, whereby to accommodate different shapes and sizes of valve stems for vulcanization.

The above and still further objects of our invention will become apparent from the following detailed specification, appended claims, and attached drawings.

Referring to the drawings, wherein like characters indicate like parts throughout the several views:

Fig. 1 is a side elevation, illustrating my device in vulcanizing position on an inner tube, with some parts being broken away and some parts being shown in section;

Fig. 2 is a vertical section, taken on the line 2—2 of Fig. 1, on an enlarged scale and with some parts being broken away;

Fig. 3 is a view corresponding to Fig. 2, showing a slightly different use of the equipment;

Fig. 4 is a view corresponding to Fig. 3, but illustrating a still different use of the equipment; and

Fig. 5 is an axial section in perspective of one of the soleplate inserts, some parts being broken away.

Referring with greater particularity to the 60

2

drawings, the numeral 1 indicates a bed plate, preferably formed from cast iron or the like and formed on its upper face with a circular recess 2, which is adapted to snugly receive a resilient displaceable pressure pad 3, preferably formed from cured rubber-like material. A bridge beam 4, shown as being arcuate in form, has one end horizontally pivotally secured to the bed plate 1 by a hinge pin 5. Adjacent its opposite end, the bridge beam is provided with a segmental recess 6 in which is seated the rounded head 7 of a clamping lever 8. Eccentrically pivoted, as indicated at 9, is the upper end of a clamping stud 10, which extends downwardly through an opening 11 in the outer end of a bridge beam 4 and into an outwardly opening slot 12 in the end of the bed plate 1. At its threaded lower end, the clamping stud 10 is equipped with an adjustable clamping nut 13. The clamping nut 13 is equipped with a circumferential flange 14 that is adapted, under downward clamping movements of the clamping lever 8, to engage shoulders 15 in the slot 12.

In its central portion, the bridge beam 4 is provided with a downwardly-opening cylindrical socket 16, which is adapted to receive a head 17 of an elongated rectangular pressure shoe 18 interposed between the bridge beam 4 and the bed plate 1. It will be noted, particularly with reference to Figs. 1 and 2, that the head 17 is arcuate in shape transversely of the pressure shoe 18, but is flat in a direction longitudinally of the pressure shoe 18 for a purpose which will hereinafter become apparent. Furthermore, the depth of the downwardly-opening cylindrical socket 16, as compared to the thickness of the head 17, is such as to permit limited rocking movements of the pressure shoe 18 in a direction transversely of said pressure shoe. A split retaining collar 19 is secured to the under side of the bridge beam 4, by means of screws or the like 20, and supports the head 17 within the cylindrical socket 16 when the bridge beam is in its raised dotted line position of Fig. 1.

45 The pressure shoe 18 is of a hollow box-like construction and contains a heating element, not shown, preferably electrical in nature and supplied with electrical current through electrical wiring 21. At its base, the pressure shoe 18 is provided with a soleplate 22 having a central recess 23, preferably circular in form. A circular soleplate insert 24 is adapted to be received within the recess 23 and may be held therein by means of a face plate 25 having resilient hooked ends 26, which are adapted to fit into notches 27 in opposite side or end walls of the pressure shoe 18.

The structure illustrated in Fig. 2 is specifically designed for use in vulcanizing of patches on inner tubes, where the repair is remote from the valve stem. When it is desired to utilize my novel

equipment for use in vulcanizing breaks in the inner tube in close proximity to the valve stem, the plate 25 and the soleplate insert 24 are removed from the soleplate 22 and a soleplate insert 28 (see Figs. 3 and 5) is inserted into the central recess 23. It will be noted that the insert 28 has a central opening 29, which is aligned with axially aligned openings 30 and 31 in the pressure shoe 18 and in the head 17 thereof and 32 in the bridge beam 4. Thus, the aligned openings 29, 30, 31, 10 and 32 are capable of receiving a valve stem *x* of any length.

When it is desired to vulcanize a new valve stem to an inner tube, a soleplate insert similar to insert 33 (see Fig. 4) is utilized. It will be observed that the insert 33 differs from the insert 28 in that it has a circumferential flange 34, which extends below the soleplate 22, thereby limiting heat and pressure to the area of the tube immediately underlying the insert 33.

Operation of clamping mechanism

When an inner tube has been placed in position for vulcanization, as indicated in Figs. 1 to 4 inclusive, the clamping nut 13 is screwed upwardly on the threaded end of clamping stud 10 until the flange 14 thereof engages the shoulders 15 in the slot 12. Thereafter, the necessary degree of pressure between the shoe 18 and the inner tube, indicated by the letter *y*, is quickly obtained by depressing the eccentrically pivoted clamping lever 8 to the full line position indicated in Fig. 1. After vulcanization, the lever 8 is elevated to the dotted line position shown by Fig. 1 and clamping nut 13 is swung outwardly of the slot 12 at which position, the bridge beam 4 and pressure shoe 18 may be elevated to the dotted line position shown in Fig. 1. It will be noted that the flange 14 of the clamping nut 13 is located adjacent one end of the clamping nut 13, whereby to allow the clamping nut 13 to be reversed on the clamping stud 10 to accommodate greater thicknesses of material between the pressure shoe 18 and the bed plate 1.

Operation of the pressure shoe

It will be observed that the normal position of the elongated pressure shoe 18 is transversely of the bridge beam 4. In this position, the pressure shoe 18 is permitted to rock in a vertical plane parallel to the bridge beam 4 and transversely to the pressure shoe 18, but is prevented from rocking in a vertical plane transversely of the bridge beam 4 and longitudinally of the pressure shoe 18 by virtue of the fact that the head 17 is rounded in one direction and straight in the other (see Figs. 1 and 2).

In prior art structures, it has been common practice to secure the pressure shoe to the bridge beam by means of a ball and socket joint, which permits rocking of the shoe in any direction. The result of this type of mounting was that, where the thickest portion of the material being vulcanized did not directly underly the ball and socket connection, the pressure shoe was tilted with respect to the bed plate and consequently brought curing heat and pressure to bear only upon one side of the raised or thick portion.

In our novel arrangement, wherein the pressure shoe 18 is mounted for rocking movements only in a vertical plane longitudinally of the

bridge beam, to compensate for varying elevations of the bridge beam due to varying thicknesses of material, parallelism between the soleplate 22 of the pressure shoe 18 and the bed plate 1 is maintained at all times, irrespective of whether the thickest portion of the material being vulcanized directly underlies the socket or not. This, of course, means that the thickest material gets the greatest pressure. However, to prevent too great a pressure being applied in any given point beneath the pressure shoe 18, we provide the thick cured rubber pressure pad, which is capable of being displaced sufficiently to compensate for the uneven pressures due to the uneven thicknesses of the material being vulcanized.

While we have disclosed a preferred embodiment of our invention as provided by section 4888 of the United States Statutes, it should be understood that the same is subject to modification without departure from the scope of the appended claims.

What we claim is:

1. In a device of the class described, a bed plate, a bridge beam, means mounting one end portion of the bridge beam for pivotal movements with respect to the bed plate on a horizontal axis, a pressure shoe interposed between the intermediate portion of the bridge beam and the bed plate and carried by the former by means of a joint permitting rotary movements of said shoe but allowing lateral swinging movements thereof in only one plane, and clamping means cooperating with the extended other end of the bridge beam.

2. In a device of the class described, a bed plate, a bridge beam element, means mounting one end portion of the bridge beam element for pivotal movements with respect to the bed plate on a horizontal axis, an elongated pressure shoe element interposed between the intermediate portion of the bridge beam element and the bed plate, a connection between the intermediate portion of said bridge beam element and the intermediate portion of the pressure shoe element comprising a socket bore in one of said elements and a head projecting from the other of said elements and contained within said socket bore, the end of the socket bore being flat and the adjacent end of the head being arcuate in one direction and being straight and parallel to the flat end of the said socket end in the other direction, and means confining said head within said socket, whereby the shoe is permitted unlimited rotary movements but is restrained from lateral swinging movements except in one plane.

MATHIAS J. DAHEIM.
FRANK L. FINN.
